US00D831607S

(12) **United States Design Patent** (10) **Patent No.:** **US D831,607 S**
(45) **Date of Patent:** **** Oct. 23, 2018**

(54) **AUDIO DEVICE**

(71) Applicant: **Bose Corporation**, Framingham, MA (US)

(72) Inventors: **Carl Johan Liden**, New York, NY (US); **Brett Tobias Tom**, San Francisco, CA (US); **German Aguirre Raeder**, Tucson, AZ (US); **Hannah Hyunjung Lee**, New Haven, CT (US)

(73) Assignee: **Bose Corporation**, Framingham, MA (US)

(**) Term: **15 Years**

(21) Appl. No.: **29/573,074**

(22) Filed: **Aug. 2, 2016**

(51) LOC (11) Cl. **14-01**

(52) U.S. Cl.

USPC **D14/205**

(58) **Field of Classification Search**

Primary Examiner — Paula Allen Greene

(57) **CLAIM**

The ornamental design for audio device, substantially as shown and described.

DESCRIPTION

FIG. 1 is a perspective view of an audio device as seen from the front, top and left side;
FIG. 2 is a front view thereof;
FIG. 3 is a left side view thereof;
FIG. 4 is a back view thereof;
FIG. 5 is a right side view thereof;
FIG. 6 is a top view thereof; and,
FIG. 7 is a bottom view thereof.

1 Claim, 7 Drawing Sheets
